[57] CLAIM

The ornamental design for a fence for a power tool, as shown and described.

DESCRIPTION

FIG. 1 is a front elevational view of a first embodiment of the present invention;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a front perspective view thereof.

In the above drawings, any broken line illustration is not part of the design sought to be patented. In addition, any views not shown thereof do not form a part of the invention.
